INTERNAL COMBUSTION ENGINE

Application filed May 16, 1928. Serial No. 278,088.

This invention relates to internal combustion engines of the two-cycle type, although some of the features are useful for four-cycle engines.

5 The principal object of the invention is to produce at low cost a relatively light, compact, powerful and durable and dependable high-speed engine of simple construction.

The crank-shaft is of the two-throw type 10 having only two wrists, which are diametrically opposite. Each wrist is operable by eight pistons, the piston-rods placed side by side and extending in various directions from the wrists to their respective cylinders. The 15 cylinders are arranged in rows which extend longitudinally of the crank-shaft, four cylinders in each row. Each of the four rows is divided into two pairs, and the cylinders in each pair are inosculated and driven by

20 the same explosion of gas, which is ignited by a single spark-plug. In other words, there are eight pairs of cylinders, four pairs working on one crank-wrist and four pairs upon the other.

All of the rows of cylinder-25 heads radiate at angles of 45 degrees from one another, thus producing a balanced action; two pistons rising while the other two descend in the same row. The pistons are very small in diameter and have a moderate 30 stroke, and the piston-rods are short so as to produce a high speed and durability with smooth action. The crank-shaft may be made of several parts. One of the wrists may be integral with the middle journal 35 portion of the shaft, and the piston-rods may be slipped upon the wrist, one after another, and suitably connected to the pistons and arranged in the cylinders. Then the other wrist may be slipped through the remaining

40 pitmen, and the pin may be rigidly secured. Upon each wrist is a sleeve, and the hubs of the pitmen fit upon the sleeve. The wrist turns within the sleeve, but the pitmen do not turn very much upon the wrist. This 45 permits relatively thin piston-rods, and avoids the weight of connecting bolts and other parts of each piston-rod.

A bypass may be provided between the pump and the engine-cylinders, and the bypass may be under the control of the auto-

mobile-driver, so that by opening the bypass he may reduce the pressure in the charging line to the engine, and hence slow down the engine, but, by closing the bypass and consequently running up the pressure in the charge line, more charge is supplied to the engine, and more power and speed are secured. From the pump-housing two manifolds run to the engine, and branches run 55 from the manifolds to the intake-ports, there being four branches from each manifold or conduit, thus supplying all eight of the intake-ports.

The use of sixteen piston-rods upon two 60 crank-wrists permits the use of a crank-shaft which is very short and therefore desirable for high speed and quietness of operation.

Other features and advantages will herein-after appear.

In the accompanying drawings, 70 Figure 1 is a cross-sectional elevation of the engine-block, showing four pistons connected to one of the crank-wrists.

Figure 2 is a longitudinal sectional elevation of the engine and pump, compressor or 75 charger.

Figure 3 is a plan of the engine partly in section, and showing the charger in diametrical section, and also indicating the battery-charging dynamo, the distributor of the ignition system, the fan and the radiator, also the carburetor and the Stewart vacuum tank.

Figure 4 is a sectional vertical elevation of the compressor for charging the engine, showing its bypass pressure regulator, and also the carburetor; the compressor operating between the carburetor and the engine.

Figure 5 is a diagrammatic sectional plan, showing a pair of intake and exhaust cylinders, the former within an intake manifold 90 chamber, and the latter within an exhaust chamber.

In the preferred form of the invention there are employed sixteen cylinders inosculated in pairs, each pair including an intake-cylinder 95 20 and an exhaust-cylinder 21, which may be placed side by side, having a common explosion-chamber or inosculating 22, 22^a. In the cylinders are separate pistons 23, 24, connected by rods 25, and pivots 26^a to wrists 27,

28 of a two-throw crank-shaft 29. The pistons in each pair move as a unit. At Figure 2 is shown a row of four cylinders, consisting of two pairs. There are shown at Figures 1 and 3 four of these rows.

As at Figure 1, the rows are evenly spaced, each row being separated from the next by an angle of 45 degrees, and the outer rows are placed at an angle of 22½ degrees from 10 a horizontal plane intersecting the crank-shaft axis. There are eight evenly spaced explosions for each revolution of the crank-shaft.

To each crank-wrist 27, 28 are articulated 15 eight rods, connecting it to eight pistons, working in eight cylinders, radiating in the four directions seen at Figure 1. The two middle rows of cylinders, indicated at 31, 32, at Figure 1, are each spaced at an angle of 20 22½ degrees from a vertical plane intersecting the axis of the crank-shaft. The outer rows 30, 33 radiate at an angle of 67½ degrees from the vertical plane. At Figures 1 and 2 it will be understood that there are 25 four rows of pistons, four in each row, half of the pistons in each row being connected to one crank-wrist and half to the other. Each row is sub-divided into two pairs, the pistons in one pair moving simultaneously in the 30 opposite direction from the pistons in the other pair in the same row, so that the reciprocating parts are mutually balancing.

Figure 3 shows that the pairs of cylinders and their respective engine-heads have an 35 echelon arrangement, agreeing with the alternating arrangement of the pitmen upon the left-hand and the right-hand crank-wrists 27, 28.

The cylinders in each pair form an engine- 40 head 33^a, as seen at Figure 2, two engine-heads in each row, and the engine-block 33^b includes the eight engine-heads in echelon arrangement, Figure 3. The heads may all be cast integral with one semi-cylindrical 45 body-part 34 having integral bottom portions 35, Figure 1.

The left-hand crank-wrist 27, Figure 2, accommodates the hubs 25^a of eight pitmen 25 and two spacing collars 25^b, of which 50 group of pitmen and collars the first and fourth, counting from the right, belong to the engine-head 36, Figure 3; the third and sixth belong to the engine-head 37; the fifth and eighth belong to the engine-head indicated at 38, and the seventh and tenth belong to engine-head 39. The second and ninth are the spacing collars 25^b. By this arrangement undue separation of the pistons in the engine-head at Figure 2 is avoided, and the capacity 55 of each explosion chamber 22 is kept at a minimum. The invention is, however, not limited to this order of the pitmen upon the crank-shaft, nor to the precise echelon arrangement shown for the engine-heads, nor 60 to the use of the spacing collars.

There is a corresponding arrangement of the pitmen of the right-hand crank-wrist 28. Two pitmen of other cylinders may intervene between the pitmen of each pair of cylinders; or, in some cases, one pitman and one spacing collar. The piston-rods in each pair are 70 separated to afford this space for the other pitmen and collars. This conduces to shortness and rigidity of the shaft, simplicity, mutual balance and smooth running.

Every down stroke of each piston is a power-stroke, thus placing this simple engine on a par with the sixteen-cylinder, eight-throw, four-cycle engine, with its thirty-two valves, of the prior art. In other words, 80 there are twice as many impulses for each revolution as can be obtained in the common sixteen-cylinder, eight-throw, four-cycle engine.

The engine-block may be closed by ends 41, 85 and there may be provided a drop portion 42 of a crank-case, also end bearings 43, 44 and a midway bearing 45 for the crank-shaft. Each cylinder may be about double the 90 length of its piston, and may extend both outwardly and inwardly from the semi-cylindrical shell 34 for compactness.

In each revolution, each pair of pistons is arrested twice, this arrest occurring at the 95 opposite end of the stroke from the other pair in the same row, Figure 2; there being two arrests in each row at each revolution, making in each revolution eight arrests altogether in the entire system of pistons. These 100 eight arrests occur at intervals of forty-five degrees for smooth running, and the engine is moreover evenly driven by means of the eight evenly spaced impulses at each revolution.

The crank-shaft may be cut from a cylindrical bar to form the crank-wrists and the journals, leaving uncut portions 46 of original diameter to serve as cranks and fly-wheels, and also leaving similar portions 47 at each side of the midway journal 29 for a similar purpose. Upon each crank-pin 105 may be placed a thin-walled split bearing collar or sleeve 48 to reduce friction between the piston-rods and the wrists. Each collar 48 may, however, be divided into four equal sections 48^a, each section equal in length to the thickness of two pitman-hubs, as seen on wrist 28, Figure 2.

The fuel for the engine, mixed air and gasoline, may be received from a carburetor and may enter the engine through a pair of manifolds 49, 50, entering the cylinder-block at its right end and extending nearly to the other end. Manifold 49 passes between the two outer cylinder rows 36, 37 at the left, and manifold 50 passes between the two outer rows at the right, Figures 1 and 3; all of the manifolds being integral with the engine-heads.

Near its entrance each manifold is enlarged 110

to form opposite chambers or reservoirs 51, each chamber enclosing or surrounding the two right-hand intake-cylinders 20, at Figure 3. At its left-hand end the manifold terminates in similar chambers 52, Figure 5, each including the two left-hand intake cylinders 20 at this end of the engine-block.

Each of the exhaust-cylinders 21 likewise passes through a chamber 53, Figure 5, which conducts the exhaust from the cylinder to an outlet 54, there being eight substantially similar outlets shown at Figure 3, extending in echelon arrangement around the middle portion of the semi-cylindrical shell of the engine-head. Each intake-cylinder may have a port 55, opening entirely around the cylinder within its intake manifold or chamber to secure maximum capacity and speed of gas-flow.

In the operation of the engine, when any piston is at the bottom of its stroke, the intake-port 55 is wide open, and the explosive compressed mixture of air and fuel is forced through the manifold and through the chamber 52 into the port 55, entering the cylinder 20 and sweeping the burned gas upwardly therein, and across through the explosion chamber 22 and down through the exhaust-cylinder 21 and out of the exhaust-port 57; the freshly entering gas thus displacing the exhaust gas, and either completely filling both cylinders and the explosion chamber, or only partially occupying them, or perhaps leaving the explosion chamber 22 and cylinder 21 filled with burned gas.

The degree to which the fresh gas displaces the exhaust gas will depend upon the speed of the engine and the pressure at which the fresh gas is supplied through the inlet-port 55 to the cylinders; such pressure and speed being variable and always under the control of the operator. As soon as the engine is in motion, the piston 23 rises, quickly closing the intake-port 55. At the same time the piston 24 rises and soon closes the exhaust-port 57. The fresh gas under pressure of say one or two pounds above atmospheric for ordinary speeds has an opportunity to expand and drive out more of the exhaust gas before the rising piston 24 fully closes the exhaust-port.

Both pistons 23, 24 continue to rise, being driven up by the crank-wrist, whereby the charge of fresh gas or the mixture of fresh and burned gas is compressed preparatory to firing the spark-plug 58, which may be placed in socket 59 directly over the intake-cylinder 20, and extend into the portion of the explosion chamber which is occupied by the compressed fresh gas, thus tending to quick and sure firing of the fresh charge, even when it only partially fills the cylinder.

The two pistons are driven down by the exhaust charge, and the exhaust-port 57 may have a lead of say 50 or 60 degrees, opening

when the crank-wrist is within 50 or 60 degrees of its lowest position. There is a substantial escape of gas through 57, and hence a substantial reduction of pressure and temperature of gas in both cylinders before the intake-port 55 opens, thus avoiding liability of igniting the fresh charge which has now to enter through the port 55. The relative narrowness of intake-port 55 guards against excessive supply of charge to the cylinders, since intake-port 55 is open later and closed earlier than exhaust-port 57.

When port 55 does open, the charge being supplied at a pressure of one or many pounds to the square inch, there may be yet enough pressure remaining in the cylinders 20, 21 to force back a portion of the fresh gas temporarily into the charging chamber or manifold, but without liability of becoming unduly mixed with the fresh gas. But upon the further exhaust of the burned gas during the final portion of the explosion strokes of the pistons, the pressure of the burned gas will diminish so far as to permit the fresh compressed gas to sweep out some or all of the burned gas, as already explained, and the cycle is repeated.

By means of an outer shell 61, there may be provided an annular space between 61 and 34, which may be subdivided by integral partitions (62, for example) into the manifolds and the intake and exhaust chambers, already described.

This semi-cylindrical irregular outer shell 61 may also serve as the bottom of a water-jacketing, the ends of which are seen at 35 and the sides at 63. Said ends and sides as well as the outer ends of all of the cylinders may be given a semi-cylindrical finish, as indicated at 64, Figure 1, to receive a detachable cap 65, which may be held by bolts (not shown) and completes the water-jacketing.

In this detachable cover 65 may be formed arches 66 rising from the pairs of cylinders and having water-tight joints therewith, to form the explosion chambers 22 into which open the spark-plug sockets 59. The inner facing of the detachable cover is finished semi-cylindrically to fit tightly upon the engine-head, and if desired a gasket may be inserted between them.

The head includes jacketings 67 for the explosion chambers, said jacketings opening at their ends into the main water-jacket, and the spark-plug sockets rising from the explosion chambers through said jacketings 67. At the crown of the water-jacketing the two arch portions 67 are merged at 68 and a delivery water-pipe 69 rises therefrom.

It will be understood that there are separate water-jacketings, one for the left end and the other for the right end of shell 34, and one outlet pipe for each water-jacketing cover, each cover being detachable independently of the other. Cooled water-pipes 69

each have branches 70 opening into the water-space of the engine at the bottom of the engine-block upon the sides thereof, these members 69 and 70 being carried by the detachable heads so that when lifting off said heads the water-system may be conveniently lifted off therewith.

It will be understood that the engine-head may be cast in one piece with the manifolds and exhaust-chambers and water-jacketing, the water-spaces being indicated by W.

Instead of making the crank-shaft all in one piece, it may be made of three pieces joined together, each wrist-pin 27 and 28 having at its right-hand end, Figure 2, a reduced portion 71, which is fitted in a socket in the crank-portion 46 or 47 and secured by a fastening pin 72. The wrist 28 may be made of one piece with the central shaft length 29, and the adjoining fly-wheel or crank-portion 47. The wrist-pin 27 may be made in one piece with the left-end fly-wheel or crank-portion 46 and the end shaft 29. The right-hand fly-wheel or crank-portion 46 may be made in one piece with the right-hand crank-portion 29. The pin 28 is inserted endwise through the hubs of the right-hand row of pitmen, and secured by the pin 72 in member 46, and then the pin 27 may be thrust through the hubs of the pitmen at the left of Figure 2, and likewise is secured by pin 72 or otherwise, thus completing a rigid inexpensive shaft, and avoiding the necessity of making each pitman of many separate parts.

The use of gears for driving the engine-charger, the electric generator and the ignition distributor may be avoided, all of these devices being compactly placed directly upon the crank-shaft or an extension 73 thereof, which may be coupled or pinned to the right-hand end of the main crank-shaft 29. This conduces to cheapness, compactness, accessibility, speed, durability, and dependability, and a water-cooling fan 74 may be secured upon the forward or right-hand portion of said shaft 73 just in rear of the radiator 75, which may be arranged at an elevation to secure proper water-circulation. This also avoids the necessity of a driving belt for the fan, which may be caused to draw the air down from the elevated radiator through a downwardly-directed conduit 76, which extends back of the radiator and down to the fan, which it encloses at 77, the part 77 being a short cylindrical shell so that revolution of the fan will draw air through the radiator and down through the conduit and then expel it rearwardly from said shell 77.

An air horn 78, diminishing from its intake end to its delivery end, may extend back from the fan at one side thereof to a carburetor 79 of any standard type, through which the warmed air and the gas mixed therewith is drawn, the carburetor being fastened by bolts 80 to the side of a novel com-

pact rotary compressor or pump, which is indicated generally as 81, said compressor being formed for compact mounting about the shaft 73 and capable of delivering the mixed air and fuel at a high pressure to the engine-cylinders.

The pump is based upon the gear-tooth principle, and includes a pinion or inner spur-gear 82, having a hub 83 whereby it is fixed upon the engine-shaft extension 73, and also an annular internal gear 84, having its inwardly-pointed teeth meshing with gear 82. The gear 84 is of larger diameter than 82 and has a hub 85 which turns upon a fixed bearing 86 eccentric to shaft 73. The shaft 73 extends through said bearing 86, and the latter may be formed upon a right-hand cover or end disk 87 of the pump, said cover fitting within the fixed drum 88 of the pump, and secured thereto against rotation. The internal gear 84 fits closely within said drum 88, and the latter, by means of an annular flange 89, is secured to an end flange 90 of the engine-head by suitable means, not shown.

Between the intake and delivery sides of the pump extends a fixed curved wall 91, forming the race portion of the pump, the inner surface of said wall being concentric with the engine-shaft 73, and the outer surface thereof being concentric with the internal gear 84. The tips of the teeth of both gears fit closely against said wall.

The gears revolve towards the right or clockwise in Figure 4, past the intake-port 92 at the bottom of the pump. Said port 92 opens into a conduit 93 which extends down from the carburetor 79. The inner edge of the port 92 is seen at 94, the right-hand end at 95, and the left-hand end at 96. It will be seen that 92 and 94 coincide with the bottoms of the notches or grooves in the gears. The teeth 97 of the spur-gear 82 draw out from the notches or grooves between the teeth 98 of the internal gear 88, thus tending to produce a vacuum into which is drawn the mixed air and fuel coming through the carburetor. The teeth 97, 98 now contact with the separating wall or race 91, and revolve in contact therewith, so that each of the notches or grooves 99 and 100 retains its charge until they pass the race 91, when the spur-teeth 97 begin to enter the notches or grooves 100 of the internal gear.

As said teeth 97 enter said grooves, they force the mixed gas and air out from the ends of the grooves and the same flows out through a port whose outer curved edge is indicated at 101, its inner curved edge at 102, and its ends at 103 and 104. Said end 104 occurs at about the point where the spur-tooth completely fills the groove in the ring-gear. This port 101 opens into a segmental conduit 105, formed upon the rear end of the pump, and said conduit opens into the intake-manifolds 49, 50 of the engine. It will be seen that as the spur-teeth enter the

grooves, the mixed gas and air is forced into the conduit and thence into the manifolds, and into the engine cylinders. The charging is rapid and at high pressure; the pump being preferably oversize for the engine. The diameter of the spur-gear may nearly equal that of the internal gear, giving the pump great capacity and compactness, and tending to overcome leakage, since the meshing of 10 teeth is quite extensive.

An advantage of this internal gear form of pump arises from the entire glove-fitting of the spur-teeth into the grooves of the internal gear at the plane which intersects the 15 axes of both gears at the right of Figure 4. The fitting is so complete that leakage of the compressed charge over into the intake side of the pump is practically prevented, so that at low cost a pump may be made which 20 will deliver compressed gas or air, or other fluid, at high pressure and speed, and with high efficiency. It will be seen that the pump may be so made that one tooth completely closes up the groove in the ring-gear, while 25 the two adjoining teeth almost close the adjoining grooves, so that leakage of gas or fluid around these teeth is negligible.

The pitch-line is preferably half way between the tips and the bases of the teeth, and 30 the teeth may have straight inclined sides, or they may have regular gear-form, such as usable in internal gear-couples; but preferably each tooth is shouldered as indicated at 106, midway between its base and its tip, and 35 the shoulders on the spur-teeth mesh with those upon the internal gear-teeth. This makes very many corners of teeth to occur between the point where the grooves are about closed up and where they begin to open 40 again, say, for example, ten or twelve corners, the purpose of the numerous corners being to baffle the fluid as it tends to work its way around between the gears. Each corner serves to baffle or retard the flow of fluid, 45 so that leaking is really prevented, and an effectual seal is thus provided between the delivery side and intake side of the pump.

The conduits 93, 105 curve around between the forward or left-hand wall 110 of the 50 pump, Figure 2, and the engine-flange 89, and are integral with both. The upper portion of the bearing 44 of the crank-shaft 29 may be projected to the right from the end 41 of the engine-head, Figure 2, being surrounded by said flange 89 and the upper and lower conduits. The body 111 of the spur-gear is fastened to the shaft 17 by means of 55 its hub 83, and occupies a position between the fixed eccentric bearing and the forward 60 wall 110 of the drum.

In assembling the parts, the spur-gear is placed in first; then the drum. The drum may be fastened to the shaft 73 either before 65 or after inserting the spur-gear within the drum. Then the internal gear 84 is inserted

in the drum in mesh with the gear 82. Then the fixed bearing 86 and cover 87 are put in position and secured to the drum 88.

The length of the teeth of the pump is seen at Figure 2, and is sufficient to deliver the proper charge, which escapes along the grooves and through the port 101 into the conduit 105. The two gears are of equal thickness, and the cover 87 packs them against the wall 110 of the charger. The gear 82 may have internal flanges 112, 113 for packing, and the latter may be recessed to fit over an annular packing 114 formed on the front side of the rear wall 110 of the drum. The inlet and delivery conduits are both on the rear side of the end of the drum, or the left-hand side at Figure 2. The shoulders 106 extend the the entire length of the teeth. This charger will deliver the charge at a pressure of many pounds per square inch above atmospheric pressure, and meet the requirements of the engine.

Any suitable air-cleaning device may be used between the horn 78 and the carburetor.

Any suitable battery charger 115 and ignition distributor 116 may be arranged upon the crank-shaft 73 between the charger and the fan. All of the driven parts may therefore be placed upon the engine shaft, and the whole engine with its appurtenances may be 90 light, compact, inexpensive and dependable.

The liquid gasoline may be fed from a Stewart vacuum tank 117, for which is arranged a vacuum tube connection 118 from the intake or vacuum conduit 93 of the pump. 100 The vacuum tank 117 has a gasoline supply pipe 119 extending down to the carburetor 79.

The speed and power of the engine may be controlled by a lever or handle through a link 120, extending forwardly from the dash of the automobile and operating an arm 121 which is provided upon a rock-shaft 122, to which is secured at 123 a shutter or valve 124, placed in a bypass 125, which extends from the high-pressure delivery conduit 105 to the low-pressure intake-conduit 93. This valve 124 is closed when it is desired to deliver the fuel to the engine at extremely high pressure. By moving the link 120 to open the valve 124, circulation is permitted from the delivery to the intake side of the pump through the bypass, and hence the pressure is reduced in the delivery conduit 105 and in the intake-manifold 49, 50, down to the required pressure. The link or rod 120 may be operated by a pedal or by a control-lever (not shown) placed convenient to the driver of the automobile; a combined pedal and steering-wheel control of a speed-governing rod being known in this art.

The position of the valve 124 determines the volume of charge flowing idly from the pump and passing to the intake side thereof, and hence determines the volume of the re-

70

maining charge which flows to the engine, and thereby regulates the speed and power of the engine. The greater the volume of charge that passes through the bypass, the less will be the volume of the charge which reaches the engine. In starting the engine, the valve 124 may be closed, and, after the engine attains speed, said valve may be gradually opened in order to reduce the speed.

10 Variations may be resorted to within the scope of the invention, and portions of the improvements may be used without others.

Having thus described my invention, I claim:

15 1. An internal combustion engine having a crank-shaft provided with only two wrists, said wrists being diametrically opposite, sixteen cylinders, said cylinders arranged in rows which extend longitudinally of the 20 crank-shaft, there being four cylinders in each row, sixteen pistons in said cylinders connected to said wrists, half of the pistons in each row for one crank-wrist and half for the other, the cylinders in each row being divided into two pairs, the cylinders in each pair being side by side and inosculated and having a spark-plug, pitmen connecting four pairs of said 30 pistons to one crank-wrist, and pitmen connecting the other four pairs of pistons to the other crank-wrist, all of the rows of cylinders radiating at angles of 45 degrees from one another to procure a mutual balancing of the pistons and to secure eight evenly-spaced explosions at each revolution of the 35 crank-shaft, each pair of cylinders forming an engine-head and there being two engine-heads in each row, the engine-heads in the different rows being in echelon or the like arrangement, and the pitmen having corresponding arrangements upon the crank-wrists, there being space between the pitmen in each pair for a plurality of other pitmen, and each of said other pitmen belonging to 40 a different engine-head, the engine-heads being all cast integral with a semi-cylindrical shell or body-part forming an engine-block.

2. An engine having the elements as set forth in claim 1, and having two intake manifolds extending longitudinally of the rows of cylinders and between said outer rows, each conduit having opposite branches to the intake cylinders, said branches forming chambers, one for each intake cylinder and each intake cylinder being surrounded by each chamber and open on all sides thereto.

3. A high-speed automobile-engine of the flexible class having a crank-shaft, pairs of inosculated cylinders provided with pistons, 60 said crank-shaft having wrists, the pistons in each pair being connected to the same crank, and the pairs of pistons being mutually balanced, the cylinders, pistons and crank-shaft being organized for effecting evenly spaced 65 explosions in sufficient number at each revolution of the shaft to produce a continuous torque thereon, one piston in each pair controlling the intake and the other controlling the exhaust, the cylinders having ports opened at the conclusions of the explosion-strokes, a carburetor, a unitary charging means common to all the intake-cylinders and driven by the engine and co-operative with said carburetor for supplying, in unmeasured volume, mixed air and fuel under constant pressure to the intake-cylinders to displace burned gases in both intake and exhaust cylinders, and a universally adjustable relief device for said charging means constantly available to the operator for varying over a wide range both the speed and the power of the engine by varying the pressure at which the mixed air and fuel is supplied to the intake-cylinders and thereby determining the proportion of spent gases to be displaced by the incoming charges, each exhaust port having substantially greater height than the intake port in the same pair of cylinders.
